B. W. KERR

HIGH TENSION SWITCH MECHANISM

Filed Jan. 14, 1926

Inventor:

Benjamin W. Kerr

By Bynes, Townsend & Brickhuston

Attorneys.

UNITED STATES PATENT OFFICE.

BENJAMIN W. KERR, OF GREENSBURG, PENNSYLVANIA, ASSIGNOR TO RAILWAY AND INDUSTRIAL ENGINEERING COMPANY, OF GREENSBURG, PENNSYLVANIA, A CORPORATION OF PENNSYLVANIA.

HIGH-TENSION-SWITCH MECHANISM.

Application filed January 14, 1926. Serial No. 81,274.

This invention relates to high-tension switches of the type used on transmission lines and exposed to atmospheric conditions.

Difficulties are sometimes encountered in connection with switches exposed to the effects of ice formed during sleet storms, causing a clogging of some of the moving contact-making parts. It is usually at such times that the necessity of isolating sections of the transmission line arises, requiring opening of switches. Clogging of the contact-making parts then causes considerable delay and inconvenience.

It is the object of the invention to provide a switch mechanism of the type referred to in which the difficulties mentioned are avoided.

For a full description of the invention reference is made to the accompanying drawings in which—

20 Fig. 1 is a side elevation of switch mechanism embodying the invention;

Fig. 2 is a plan view thereof; and

Fig. 3 is a section on line 3—3, Fig. 1.

In the drawings 10 represents a switch arm hinged on a post 11 to which one section of the line is connected. At its free end arm 10 carries a housing 12 containing jaws 13 preferably supported by springs 14. The housing 12 forms a conductive part of the switch mechanism.

The jaws 13 are normally in contact relation with a stationary vertical blade 15 to which the other section of the line is connected.

35 The housing 12 is pivotally connected at the end of arm 10 and connected by a parallel-motion link 16 to lug 11^a extending upwardly at an angle from post 11.

The operation is obvious. When the arm 40 10 is angularly turned from the full line position to the dotted line position in Fig. 1, to open the switch, the housing 12 is maintained in vertical position by the parallel-motion link 16 with the result that the contact mechanism within the housing is at all times protected against the weather.

While I prefer a parallel-motion mechanism, i. e. a pivoted link disposed parallel to

the arm 10, and while such an arrangement naturally affords the best protection, there 50 is, of course, no necessity for using link motion maintaining the housing in strictly vertical position. The essential point is mechanism for maintaining the housing in positions which afford substantially protection 55 of the mechanism enclosed.

The link 16 may be made of copper or other metal having high conductivity and thus form practically a part of the switch mechanism proper.

60 The switch, like all high tension switches, is in practice mounted on insulators, as is well understood. However, the support and the switch operating means form no part of the invention, and have been omitted from 65 the drawings.

The switch mechanism illustrated shows the application of spring-actuated jaws. While I preferably use jaws of this type, the invention may of course be carried out 70 with other forms of contact-making and breaking elements.

I claim:

1. In a switch mechanism, the combination of switch blade pivotally mounted at 75 one end and carrying a contact movable with respect to the blade at the other end, a second contact for cooperation therewith, a housing movably mounted on the switch blade, and means operative in all angular positions of the switch arm for maintaining the housing in position to protect the movable contact, said means including a link parallel to the blade in all positions thereof. 80

2. In a switch mechanism, the combination of a switch blade pivotally mounted at one end and carrying a contact movable with respect to the blade at the other end, a second contact for cooperation therewith, a housing movably mounted on the switch 90 blade, and means operative in all angular positions of the switch arm for maintaining the housing in position to protect the movable contact, said means including a link parallel to the switch blade in all positions 95 thereof, an integral lug on the pivotal sup-

port for the switch blade, and means to pivotally connect the link and the lug.

3. In a switch mechanism, a support, a switch blade and an operating arm pivoted to said support, a contact at the outer end of said blade, and a housing enclosing said contact, said housing being pivoted to said

blade and operating arm to complete a four element parallel-motion linkage, whereby the housing remains in vertical position in all ¹⁰ positions of the said blade.

In testimony whereof, I affix my signature.

BENJAMIN W. KERR.
